UNITED STATES PATENT OFFICE.

DANIEL E. E. WOODSIDE, OF YOUNGSTOWN, OHIO, ASSIGNOR TO THE YOUNGSTOWN SHEET AND TUBE COMPANY, OF YOUNGSTOWN, OHIO, A CORPORATION OF OHIO.

TRANSFER MECHANISM FOR LAP-WELD TUBING.

1,159,561.

Specification of Letters Patent.

Patented Nov. 9, 1915.

Application filed January 29, 1915. Serial No. 5,109.

To all whom it may concern:

Be it known that I, DANIEL E. E. Woodside, a citizen of the United States, residing at Youngstown, in the county of Mahoning and State of Ohio, have invented new and useful Improvements in Transfer Mechanism for Lap-Weld Tubing, of which the following is a specification.

My invention relates to mechanism for transferring lap-weld tubing sidewise from one welding-trough over an adjacent welding-trough.

It is the object of my invention to provide a simple mechanism by which tubing in one of two parallel troughs at the rear end of a lap-weld furnace may be transferred sidewise over the other welding-trough. Heretofore it has been common to provide arms for lifting the tubes out of one trough and carrying them over the other trough. I have simplified the mechanism by bodily lifting or swinging one welding-trough with a tube thereon over the other welding-trough.

My invention further consists in details of the mechanism whereby the troughs are supported and operated.

Referring to the accompanying drawings, Figure 1 is a plan of one end of a pair of welding-troughs equipped with my invention; Fig. 2, a cross-section on the line II--II, Fig. 1; Fig. 3, a side elevation of a second form of my invention with parts broken away; Fig. 4, a cross-section on the line IV--IV, Fig. 3; Fig. 5, a cross-section on the line V--V, Fig. 3; and Fig. 6, a cross-section on a reduced scale on the line VI--VI, Fig. 3.

Referring first to Figs. 1 and 2, 1 and 2 represent a pair of welding-troughs for receiving pipes as they are discharged from the welding rolls situated at the rear end of a lap-weld furnace. I have not illustrated the furnace and rolls as they are well known in connection with pairs of welding-troughs located as above described. The welding-trough 1 normally rests on the top of pillars near the ends of the trough, one pillar 3 being shown. The trough is secured to the rock-shaft 4 which is parallel with the trough and supported by the pillars 3. To one side of the trough 1 I pivotally connect one end of the tilting skids 5, which have their free ends arranged to direct pipes downwardly to the stationary skids 6. The

rock-shaft 4 is provided with the arm 7 having its outer end pivoted to one end of the links 8, the other end being pivoted to the piston-rod 9 of the hydraulic motor 10. When it is desired to transfer the pipe 11 from the trough 1 to the skids, the motor 10 is operated to cause the trough 1 to move from its full-line position to its dotted position (Fig. 2), whereupon the pipe 11 rolls out of the trough 1, as shown on Fig. 2, and down the skids 5 to the skids 6, on which a pipe 12 is shown. The welding-trough 2 is arranged at that side of the trough 2 which is opposite the skids 5. Its ends are supported by the legs 13, having the curved arms 14 connected to the rock-shaft 15. These arms 14 have their curves extending downwardly from the troughs and then upwardly in the form of the letter U, one leg of the U bearing the trough and the other being connected to the shaft 15. The curves are so shaped that the trough 1 is in the same when the trough 2 is swung up on the shaft 15 to the dotted position (Fig. 2). The shaft 15 is provided with the arm 16 having its outer end pivoted to the links 17, to which the piston rod 18 of the hydraulic or other motor 19 is pivoted.

Referring now to Figs. 3 to 6, the parts thereon corresponding in function to parts on Figs. 1 and 2 have the same reference numerals as on Figs. 1 and 2 with the exponent letter a. The rock-shaft 15^a has its ends mounted in the housings 20 and is provided with the collar 21 keyed thereon. The collar has the opposite arms 16^a and 16^b, the former being connected by the links 17^a to the piston-rod or plunger 18^a of the motor 19^a, and the latter being connected by the links 17^b to the piston-rod or plunger 18^b of the motor 19^b. To the shaft 15^a are keyed the collars 22 which carry the arms 14^a, supporting at their outer ends the legs 13^a. The trough 2^a is supported on the top of these legs, which rest normally on the block 23 on the bed 24 of the apparatus. The rock-shaft 4^a is secured to the trough 1^a which is between the shaft 4^a and the trough 2^a. To the arm 7^a on the shaft 4^a, carried by the bearings 29, I secure the upper end of the links 8^a, the lower end of the links being connected to the arm 25 on the collar 26 which is loosely mounted on the shaft 15^a. This collar carries the opposite arms 27 and 28, the former being linked to the piston 11^a

rod or plunger 9^a of the motor 10^a and the latter being linked to the piston-rod or plunger 9^b of the motor 10^b. When it is desired to discharge a pipe in the trough 1^a upon the skids 6^a (only one shown) the motor 10^a is operated which causes the plunger 9^a to oscillate on the shaft 15^a toward the right, thereby lifting the arm 25, the links 8^a and the arm 7^a. The lifting of the arm 7^a oscillates the shaft 4^a so as to cause the trough 1^a to be swung up over the shaft on the dotted lines above the same (Fig. 4) and to discharge the pipe therein upon the said skids. The trough is returned to its normal position by the motor 10^b through the plunger 9^b, the arm 28, the collar 26, the arm 25, the links 8^a, the arm 7^a, and the shaft 4^a. When it is desired to discharge a pipe in the trough 2^a upon the skids 6^a, the motor 19^a is operated, causing the plunger 18^a, the links 17^a, and the arm 16^a to rise. The upward movement of the arm 16^a oscillates the shaft 15^a toward the left, thereby causing the collars 22 keyed on the shaft to lift the arms 14^a together with the legs 13^a and the trough 2^a. The latter moves up on the dotted lines (Fig. 4) on an arc having its center on the shaft 15^a, the radius of this arc being sufficiently long to allow the trough 2^a to pass over the trough 1^a and discharge a pipe therein upon the skids 6^a in the same manner that the trough 2 passes

over the trough 1 and discharges the pipe 11 therein upon the skids 6. The trough 2^a is returned to normal position by the motor 19^b through the plunger 18^b, the links 17^b, the arm 16^b, the shaft 15^a, the collars 22, the arms 14^a, and the legs 13^a. By means of the screws 29' the apparatus can be raised or lowered so that the troughs will be at the proper height to receive pipe from the welding rolls.

I claim—

1. A pair of welding-troughs arranged side by side, and means whereby one of the troughs is moved relatively to the other trough so as to pass over the second trough and discharge a pipe therein on the opposite side of the second trough.

2. A pair of welding-troughs arranged side by side, a receiving table arranged at the outer side of one trough, means for tilting the said trough and discharging a pipe in the said trough upon the table, and means movable relatively to the said trough for lifting the other trough over the said tilting trough and discharging a pipe in the second trough upon the table.

Signed at Youngstown, Ohio, this 26th day of January 1915.

DANIEL E. E. WOODSIDE.
